THERMAL TIMER FOR TOASTERS

John R. Gomersall, Elgin, Ill., assignor to McGraw Electric Company, Elgin, Ill., a corporation of Delaware

Application March 29, 1940, Serial No. 326,576

8 Claims. (Cl. 161—16)

My invention relates to automatic electric toasters and more particularly to thermal timing means to determine the duration of a toasting operation.

An object of my invention is to provide a relatively simple thermal timer structure which may be associated with an automatic electric toaster and control the duration of successive toasting operations thereof.

Other objects of my invention will either be apparent from the description of a form of device embodying my invention now preferred by me or will be specifically pointed out therein and set forth in the appended claims.

In the drawings.

Figure 1 is a central vertical sectional view on the line 1—1 of Fig. 2, the parts being shown in non-toasting position.

Fig. 2 is a front elevational and sectional view on the line 2—2 of Fig. 1, the parts being shown in non-toasting position.

Fig. 3 is an enlarged fragmentary front sectional view taken on the line 3—3 of Fig. 6, showing the parts in toasting positions.

Fig. 4 is a fragmentary sectional plan view on the line 4—4 of Fig. 3 showing the parts in toasting position.

Fig. 5 is a fragmentary detail sectional view on the line 5—5 of Fig. 4 showing the parts in normal or non-operating position.

Fig. 6 is a fragmentary view showing the front end of the toaster as seen when looking at the bottom of the front end portion of the toaster with the cover member removed.

Fig. 7 is a perspective view showing some of the parts as seen in Fig. 6, in non-operating position and on a slightly enlarged scale.

Fig. 8 is a fragmentary detailed sectional view on the line 8—8 of Fig. 9 showing part of the means for varying the operating time of the toaster.

Figs. 9, 10, 11 and 12 are fragmentary detail sectional views on the line 9—9 of Fig. 3 showing the parts in the positions occupied by them during the heat-up cool-off operation of the bimetal bar.

Fig. 13 is a fragmentary detail sectional view taken on the line 13—13 of Fig. 12, and.

Fig. 14 is a wiring diagram showing the switches in initial or neutral positions.

I have elected to show my novel form of thermal timer and detent release structure as associated with a two-slice oven type automatic toaster in which the toast-heating elements are energized only during the successive toasting operations.

A toaster, designated generally by the numeral 21, comprises a skeleton base frame 23 which may be made of a suitable moulded composition material and which has mounted thereon against

its upper face a bottom plate 25 and which also has mounted adjacent its bottom edge a crumb tray 27, all in a manner well known in the art.

The toaster includes further a plurality of 5 planar vertically extending heating elements 29 each of these heating elements including one or more plates 31 of thin electric insulating material, such as mica, having wound thereon resistor strip or wire 33. While I have not illustrated the individual heating elements 29, they are already old and well known in the art and their location and arrangement in a toaster structure of this kind is clearly shown in Ireland Patent No. 2,001,362 assigned to the same assignee 15 as is the present application.

The toaster structure includes further a rear intermediate plate 35 and a front intermediate plate or wall 37 cooperating with the outermost heating elements 29 to provide toasting chambers in the toaster structure, the number of such toasting chambers constituted by spaced pairs of vertically extending toast-heating elements and portions of the front and of the rear intermediate walls equaling the number of slices of bread which 25 can be toasted simultaneously.

The toaster structure includes further a casing 39 comprising a front and a rear wall and two side walls cooperating with a cover 41 to substantially completely enclose the toasting chambers as well as a mechanism chamber 43 located 30 in front of the front intermediate wall 37.

I may provide a vertical standard 45 in the mechanism chamber 43, the lower end of this standard being supported as by the top part of a thermal timer casing 47 while the upper end thereof may be supported in proper operative position by a bracket 49 secured to the front intermediate wall 37.

One or more bread carriers 51, equal in number to the number of slices of bread which can be toasted simultaneously and for which the toaster structure is designed and constructed, are arranged to have reciprocal vertical movement in the individual toasting chambers. The bread carriers have rear end portions extending through slots 53 in the rear intermediate wall and front end portions extending through slots 55 in the front intermediate wall 37 so that the bread carriers may be guided in their respective vertical movements into upper or non-toasting positions and into lower or toasting positions relatively to the toast-heating elements hereinbefore described. Means for biasing the carriers into their upper non-toasting positions may include a 45 coil spring 57 having its lower end secured to the bread carriers in a manner to be hereinafter described while its upper end is secured to bracket 49.

Means for causing downward movement of the 50 carriers may include a carriage plate 59 verti-

cally slidable upon the standard 45 and having rearwardly extending lateral portions 81 mechanically connected to the front end portions of the bread carriers, all in a manner well known in the art. An auxiliary carriage member 63 may be loosely mounted on carriage plate 59 and have a forwardly extending bar portion 65 on which is mounted an actuating knob 61 upon which pressure may be applied by an operator to cause downward movement of the carriage plate and of the carriers against the bias of coil spring 57.

A twin conductor cord 69 is provided and extends into the toaster structure through a bushing 71 of electric insulating material, the conductors being connected to a plurality of terminal members 73, all in a manner well known in the art. All of the details hereinbefore described are already old and well known in the art and have been described only in order to more clearly set forth the operation of the thermal timer positioned within the auxiliary casing 47.

The carriage plate 59 has mounted thereon a roller 75 on a stub shaft or pin 77, secured to a bracket 78, this roller and pin moving downwardly with the bread carriers, the roller being adapted to engage a catch member 79, shown more particularly in Fig. 5 of the drawings. The catch member 79 is provided with an upper hooked portion 81 and is pivotally mounted on a pin 83 which pin may be supported by a slotted guide member 85 also shown in Fig. 5 of the drawings. The downwardly moving roller 75 will engage an inclined surface of the central portion of member 79 causing turning movement thereof in a clockwise direction against a biasing spring 87 until an extension 89 thereof engages a pivotally mounted detent 91. The upper end of detent arm 91 is provided with a hooked portion shown, for instance, in Figs. 9 to 12 inclusive so that it may engage end portion 89 of the catch 79 and hold it in locking or holding position with regard to the roller 75 to thereby cause the bread carriers to remain in their lowered position until released therefrom by the thermal timer herein-after to be described. The detent arm 91 is pivotally supported on a bracket plate 92 secured against the bottom surface of the top part of casing 47.

The carriage plate 59 is provided with a lateral projection 93 which bracket portion is adapted to engage an actuating rod 95 of a control switch for the toast-heating elements, this switch comprising a substantially fixed contact 97 mounted on a plate 99 of electric insulating material within the housing 47 and including also a spring contact arm 101 adapted to be pressed downwardly by actuating rod 95 through a compression spring 103 both of which are positioned in a tubular guide 105 secured to the top wall of casing 47. All of the details hereinbefore described are old and well known in the art and constitute no part of my present invention.

The timer includes a bimetal bar 107 having one end fixedly supported on a bracket 109 which bracket may be mounted on electric-insulating plate 99 or in any other suitable manner. An auxiliary heater 111 is insulatedly mounted on bimetal bar 107 and, as shown in Fig. 14 of the diagram of connections, this auxiliary heater, when energized, is connected in electric series circuit relation relatively to the toast-heating elements 29. The flexing or movable end of bimetal bar 107 is shown in its initial or cool position in Fig. 9 of the drawings and will, when heated by energization of the auxiliary heater 111, move to-

ward the left as is shown more particularly in Fig. 10 of the drawings.

I provide a detent-actuating bar 113 which has one end thereof pivotally connected to an arm 114 pivotally supported on the same pin as is detent 91. The other end of actuating bar 113 is provided with a shouldered end portion 115 of part of its width while the other part thereof has an angularly extending cam surface 117. Arm 91 is supported on the same pivot pin as is arm 114, but is movable relatively thereto to permit independent movement of arm 91 in a clockwise direction as seen in Figs. 9 to 12 when the extension 89 of member 78 is locked in position by member 91 when the bread carrier is held in toasting position. Arm 91 has a lateral projection 118 thereon adapted to be engaged by arm 114 when the latter is moved in a clockwise direction by bar 113 because of the latter being moved toward the right (as seen in Fig. 11) by the cooling bimetal bar 107 as will be described later.

Bar 113 is provided with an extended slot 119 therein, a reduced portion of a pivotally mounted lever arm 121 fitting into this extended slot. The other end of lever arm 121 engages a resilient contact arm 123 of an auxiliary heater control switch, the other part of this switch including a substantially fixed contact arm 125. Contact arm 123 is so constructed that it tends to engage the fixed contact 125. Lever arm 121 is provided with an upwardly extending portion 127 having a hooked end and extending through the upper wall of auxiliary casing 47 as will be seen for instance in Figs. 1 and 2 of the drawings. A spring bar 129 engages the upper hooked end of projection 127 to cause extension 127 to be biased upwardly whereby that end of lever arm 121 engaging spring contact arm 123 is moved downwardly to thereby hold the auxiliary switch comprising members 123 and 125 in open or auxiliary heater energizing position. It may be here pointed out that the lower end of carriage plate 59 is adapted to engage the outer movable end of spring arm 129 when the carriage plate has been moved into its lowermost position to remove the bias of extension 127 and of lever arm 121 hereinbefore described. The bias of lever arm 121 provided normally by spring bar 129 has the result that actuating bar 113 is normally and initially held out of the path of movement of the bimetal bar 107 during the heat-up period thereof; when, as hereinbefore stated, it will move toward the left as seen in Figs. 9 and 10 of the drawings.

A member for holding the actuating bar 113 in its normally biased position includes an arm 131 pivotally mounted at its lower end on plate 92. The movable end of arm 131 is provided with a projection 133 adapted to engage against one edge of the shouldered part 115 of detent-actuating bar 113. The movable end of arm 131 is provided with a tubular portion 135. A rod 137 having a cam-shaped projection 139 (see Fig. 6) is adjustably movable within the tubular member 135 as by a link 141 connected to a crank arm or plate 143 which is mounted on and adapted to be turned by a knob 144 mounted on a short shaft 145 (see Figs. 2 and 6). Since one end of the bimetal bar 107 is held in fixed position, the main portion thereof will flex into arcuate shape so that substantially only the end portion of the bimetal bar will engage cam surface 139 and it is obvious that if this cam surface is in the position shown in Fig. 6 of the drawings, such engagement will occur sooner than

would be the case if the shaft 145 had been turned by its knob to cause movement of cam surface 139 toward the right, as seen in Fig. 6. It is obvious that the time required to heat bimetal bar 107 to the temperature necessary to cause it to engage the right-hand end of cam surface 139, (when the latter is in the position shown in Fig. 6) will be less than the time required to cause heating of the bimetal bar and engagement thereof with the left-hand end portion of cam surface 138 thereby providing means for varying the duration of a toasting operation.

It has already been hereinbefore stated that spring arm 129 is moved downwardly out of engagement with the projection 121 when the bread carriers are in their lowermost or toasting positions, the positions of parts of the timer and of the carriers then being that shown in Fig. 3 of the drawings so that the tendency of spring contact arm 123 is to press the right-hand end of lever arm 121 upwardly thereby holding the outer end of actuating bar 113 downwardly against projection 133 during the heating-up period of the bimetal bar.

Fig. 10 of the drawings shows the next step in the operation of the bimetal bar when it has engaged cam surface 139 and caused turning movement of arm 131 in a counter-clockwise direction, as seen in Figs. 9 to 12 inclusive, whereby projection 133, which has been acting as a stop member relatively to actuating bar 113, is moved out of engagement with actuating bar 113 and resultant closing movement of spring contact arm 123 with its cooperating contact 125 whereby auxiliary heater 111 is short-circuited or de-energized.

It will be noted by reference to Fig. 10 of the drawings, that the shouldered end of bar 113 has been moved into a position where it is in the path of return movement of the now cooling bimetal bar and Fig. 11 of the drawings illustrates the next step during the cooling of the bimetal bar when it has engaged shouldered end 115 of the actuating bar 113, caused longitudinal movement thereof with resultant turning movement, in a clockwise direction, of the detent arm 91 because of the engagement of arm 114 with projection 116, whereby release thereof from catch portion 89 is effected with resultant turning movement of the catch 79 in a counter-clockwise direction and resultant upward movement of the bread carriers into their upper or non-toasting positions and simultaneous opening of the main switch controlling the toast-heating elements. A shock absorber structure 148 comprising an air cylinder and a piston and piston rod may be connected to the bracket 49 and to the carriage 59 in a manner well known in the art.

Since spring arm 129 was held in its downwardly position, as shown in Fig. 3 of the drawings, during a toasting operation, and since it will be disengaged from carriage plate 59 when the latter moves upwardly, its biasing effect on projection 127 will now again be operative and cause upward movement of actuating bar 113, or, as may be stated in other words, will cause a turning movement of bar 121 on its pivot with resultant turning movement of bar 113 in a clockwise direction so that the angular surface 117 will move past the stop member 133 to permit of arm 131 being turned in a clockwise direction under the influence of a small spring 147 provided for that purpose. It may be here pointed out that spring 147 has one end thereof connected to arm 131 and its other end connected to detent arm 91

thereby biasing both members in the desired normal or initial positions. A stop pin 148 fixed in bracket plate 92 limits the turning movement of arms 91 and 114 in one direction.

It will be evident from the above description that I provide a relatively simple mechanical structure actuatable in sequence in certain predetermined steps by a bimetal bar having a flexing end portion adapted to engage an adjustable pivotally supported member which, when moved by the heated bimetal bar, will cause movement of a detent-actuating bar into the path of return movement of the bimetal member during the cooling thereof. The bimetal bar is effective, as has hereinbefore been described, to cause de-energization of a small auxiliary heating element thermally associated therewith when the bimetal bar has been heated to an adjustable predetermined temperature to thereafter cause cooling of the bimetal bar under a draft of air flowing through the auxiliary casing 47 as by louvers 151 shown in Figs. 2 and 3 of the drawings.

It will be further evident from the hereinbefore described operation of the device that a spring bar is made effective upon upward movement of the bread carriers to cause return to their initial positions of certain parts of the timer so that it is only necessary to again move the bread carriers and slices of bread placed thereon downwardly by pressure on the knob 67 to initiate another toasting operation.

Various modifications may be made in the structure herein described and shown in the drawings without departing from the spirit and scope of my invention and all such modifications are to be considered as being covered by the appended claims.

I claim as my invention:

1. A thermal timer for an automatic electric toaster comprising a toast-heating element, a control switch therefor normally yielding biased to open position, means for closing said switch to initiate a toasting operation and a pivotally mounted detent arm for holding said switch in closed position, said thermal timer including a bimetal bar having one end free to move in response to changes of temperature, means to cause heating and then cooling of the bimetal bar, a detent-actuating bar having one end thereof pivotally connected to the detent arm, a member spring biased to normally hold the other end of the detent-actuating bar out of the path of movement of the bimetal bar when the same is being heated and engageable by said bimetal bar when the same has been heated to a given temperature to be moved out of holding engagement with the detent-actuating bar to cause the latter to move into the path of movement of the bimetal bar, the cooling bimetal bar engaging and moving said detent-actuating bar to cause releasing movement of the detent arm with resulting opening of the control switch.

2. A thermal timer for an automatic electric toaster comprising a toast-heating element, a bread carrier movable into toasting and non-toasting positions relatively to the toast-heating element, means to normally yieldingly bias the carrier into non-toasting position, means to move said carrier into toasting position and a pivotally mounted detent arm effective to hold the bread carrier in toasting position, said thermal timer including a bimetal bar having a portion free to move in response to temperature changes, means to cause heating and then cooling thereof, a detent-actuating member having

one end operatively engaging said detent arm, means for normally holding the other end of the detent-actuating member out of the path of movement of the bimetal bar when the same is heated and engageable by the bimetal bar when it has been heated to a predetermined temperature to be moved thereby out of holding engagement with the detent-actuating arm to cause the latter to move into the path of movement of the bimetal bar, the cooling bimetal bar engaging and moving said detent-actuating arm to cause releasing movement of the detent arm and resultant movement of the bread carrier into non-toasting position.

3. A thermal timer for an automatic electric toaster comprising a toast-heating element, a bread carrier movable into toasting and non-toasting positions relatively to the toast-heating element, means to normally yieldingly bias the carrier into non-toasting position, means to move said carrier into toasting position and a pivotally mounted detent arm effective to hold the bread carrier in toasting position, said thermal timer including a bimetal bar having a portion free to move in response to temperature changes, an electric heater in heat-transmitting relation to the bimetal bar, a switch for short-circuiting said electric heater normally biased to closed position, a detent-arm-actuating bar having one end connected to the detent arm, a pivotally mounted member spring biased to normally hold the other end of the detent-arm-actuating bar out of the path of movement of the bimetal bar, a lever arm pivotally mounted intermediate its ends having one end operatively engaging said electric heater switch and having its other end interfitting and moving with said actuating bar, spring means engaging said lever arm to normally cause it to hold the short-circuiting switch in open position, means connected with the bread carrier to counteract said spring means when the carrier has been moved into toasting position, the heated bimetal bar engaging said pivotally mounted member at a predetermined temperature thereof, to move it out of holding engagement with said actuating bar, cause the short-circuiting switch to move to closed position to deenergize said electric heater and cause the actuating bar to move into the path of movement of the cooling bimetal bar, said cooling bimetal bar engaging said actuating bar to cause detent arm releasing movement, return of the bread carrier to non-toasting position, termination of the counteracting effect on the spring means, movement of the short-circuiting switch to open position and return of the pivotally mounted member to its holding position.

4. A device as set forth in claim 2 in which the means engageable by the bimetal bar is provided with a cam surface contacted by the heated bimetal bar and manual means for moving the cam surface to vary the predetermined temperature at which the bimetal bar engages it.

5. A device as set forth in claim 3 in which the pivotally mounted member is provided with a manually-adjustable cam surface to cause variation in the temperature at which the bimetal bar engages the pivotally mounted member.

6. A thermal timer for an automatic electric toaster comprising a toast-heating element, a control switch therefor normally yieldingly bi-

ased to open position, means for closing said switch to initiate a toasting operation and a detent means for holding said switch in closed position, said thermal timer comprising a bimetal bar having a portion thereof free to move under temperature changes, means to cause heating and then cooling thereof, a detent-actuating bar, a member for normally holding the detent-actuating bar out of the path of movement of the moving portion of the heating bimetal bar and engageable by said bimetal bar when it has been heated to a predetermined temperature to be moved out of its holding engagement with said detent-actuating bar to cause the latter to move into the path of movement of the bimetal bar and simultaneously to cause cooling of the bimetal bar, said bimetal bar engaging said detent-actuating bar at a predetermined lower temperature to cause detent-releasing movement thereof and opening of the switch.

7. A device as set forth in claim 6 in which the member engageable by the heating bimetal bar includes means actuatable at the will of an operator to vary said predetermined temperature at which engagement occurs, the lower predetermined temperature at which the cooling bimetal bar engages said detent-actuating bar remaining constant.

8. A thermal timer for an automatic electric toaster comprising a toast-heating element, a control switch therefor yieldingly biased to open position, means for closing said switch to initiate a toasting operation and a detent arm for holding said switch closed, said thermal timer including a bimetal bar having a portion free to move under temperature changes, an auxiliary electric heater in heat-transmitting relation to the bimetal bar, a switch for controlling the auxiliary heater and inherently biased to heater-deenergizing closed position, a lever arm engaging said auxiliary heater switch, a spring engaging said lever arm and normally effective to engage and cause the lever arm to hold the auxiliary heater switch in heater-energizing open position and moved out of engagement with the lever arm by said switch-closing means when closing said switch, a detent-actuating bar pivotally connected at one end to said detent arm and having a shouldered and angularly-extending other end pivotally connected with said lever arm, a pivotally-mounted member normally biased into engagement with said other end of said detent-actuating bar to hold the latter out of the path of movement of the heated bimetal bar, said bimetal bar engaging said pivotally-mounted member at an adjustable predetermined temperature to move said member and cause movement of the lever arm and closing of the auxiliary heater switch and cause said detent-actuating bar to move its shoulder into the path of movement of the cooling bimetal bar simultaneously, said bimetal bar engaging the shouldered end portion of the detent-actuating bar at a predetermined lower temperature to cause release movement of the detent, opening of the control switch for the toast-heating element, reengagement of the lever arm by said spring with resultant opening of the auxiliary heater switch and movement of the detent-actuating bar out of the path of movement of the bimetal bar.

JOHN R. GOMERSALL.
